UNITED STATES PATENT OFFICE.

GUY L. BONHAM, OF HARTFORD, CONNECTICUT.

CAR-MOVER.

1,391,715.

Specification of Letters Patent. Patented Sept. 27, 1921.

Application filed July 6, 1920. Serial No. 394,032.

To all whom it may concern:

Be it known that I, GUY L. BONHAM, a citizen of the United States, residing at Hartford, in the county of Hartford and 5 State of Connecticut, have invented a new and useful Car-Mover, of which the following is a specification.

This invention relates to car movers and is designed more especially as an improvement upon the structure disclosed in my Patent No. 1,343,430, issued to me on June 15, 1920.

It has been found that the thickness of car wheels varies at different points along 15 the circumference. Furthermore some car wheels have uneven curved side surfaces while others have uneven flat side surfaces. One of the objects of the present invention is to provide a car mover with gripping jaws 20 adapted to adjust themselves to wheels of different thicknesses and to uneven surfaces so that a secure, non-slipping grip will be obtained under all conditions.

A still further object is to provide simple 25 and efficient mechanism which not only enables the jaws to properly grip the wheel therebetween but also allows the jaws to be simultaneously shifted out of engagement with the wheel prior to being reapplied to 30 the wheel at the beginning of the power or car moving action of the device.

A still further object is to provide means 35 for protecting the mechanism so that it will not be damaged by careless or rough handling.

With the foregoing and other objects in view, which will appear as the description proceeds, the invention resides in the combination and arrangement of parts and in 40 the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

50 Figure 1 is a side elevation of the car mover, a portion of the pedestal being broken away.

Fig. 2 is a plan view of the yoke or gripping head in position on a wheel, a portion 55 of which has been shown.

Fig. 3 is an enlarged top plan view of the

gripping head, the jaw equalizing mechanism being shown partly in section and partly in elevation.

Fig. 4 is a section on line 4—4, Fig. 3.

Fig. 5 is a section on line 5—5, Fig. 3, the releasing slide being shown in elevation.

Fig. 6 is a plan view of the releasing slide.

Fig. 7 is a plan view of the yoke or gripping head and showing a modified form of 65 equalizing mechanism, the housing of said mechanism being in section.

Fig. 8 is a section on 8—8, Fig. 7.

Referring to the figures by characters of reference 1 designates a pedestal mounted on 70 a base 2 adapted to straddle and to slide upon a rail R. In the pedestal is slidably mounted a curved stem 3 adapted to be operated by a lever a portion of which has been indicated at 4. The particular means 75 for transmitting motion from the lever to the stem has not been shown as it constitutes no part of the present invention. Such mechanism, however, can be the same as that disclosed in my patent hereinbefore men- 80 tioned.

A yoke or gripping head 5 is swiveled or otherwise mounted on the upper end of the stem 3 and is adapted to straddle the peripheral portion of a car wheel a portion of 85 which has been indicated at W. Mounted for rotation in the end portions of the yoke are parallel rods 6 to which are secured gripping jaws 7 having toothed gripping faces as indicated at 8'. The rods 6 project 90 from one face of the yoke and are provided with crank arms 8 connected by rods 9 to bell cranks 10. These bell cranks are fulcrumed as at 11 on one face of the gripping head, the two bell cranks being oppositely 95 disposed and having their upper ends connected by a coiled spring 12. This spring thus acts to pull through the rods 9 upon the crank 8 so as to hold the toothed faces 8' of the jaws normally drawn toward each 100 other.

The lower arms of the bell cranks 10 are extended toward each other, as shown at 13 and overhang studs 14 extending from oppositely projecting arms 15 on a slide 16. 105 This slide has a longitudinal slot 17 in which is arranged a guide screw 18 or the like. The sides of the slide are reduced, as indicated at 19 and are lapped by guide screws 20 or the like. The slide 16 projects downwardly below the gripping head. A housing 21 is secured to the gripping head and

serves to protect the bell cranks 10, crank arms 8, and parts coöperating therewith. The slide 16, however, projects below this housing as clearly indicated in Fig. 4.

5 It will be apparent that when the gripping head is lowered the slide 16 will come into contact with the upper end of the pedestal 1 and thus be shifted upwardly relative to the gripping head or, in other words, 10 will be held stationary while the gripping head continues its downward movement. As a result of this relative movement the bell cranks 10 will be swung apart against the action of the spring 12 and the jaws 8 will 15 also be swung apart. Consequently the jack can be moved toward the wheel W and said wheel will be received freely between the jaws 8. As soon as the stem 3 is moved upwardly by means of the lever 4 the slide 20 16 will be lifted off of the pedestal 1 whereupon the spring 12 will draw the jaws 8 toward each other and cause them to bind upon opposed faces of the wheel W. This gripping action of the jaws will be equalized 25 automatically and any variations in thickness or configuration of the wheel will not reduce the gripping action. After the jaws have engaged the wheel therebetween the continued upward movement of the stem 30 3 will result in these jaws moving the wheel with the ascending head 5 with the result that the wheel will be moved along the rail. By reversing the lever 4 the gripping head will be lowered, the toothed faces of the 35 jaws sliding downwardly along the opposed surfaces of the wheel until the gripping head reaches its lowermost position at which time the slide 16 is again actuated to open the jaws and arrange them so as to readily 40 straddle the wheel when the jack is again slid in the direction thereof.

It is to be understood that other means than those described may be employed for causing the jaws to properly engage wheels 45 of any thickness or having irregular surfaces. For example, and as shown in Figs. 7 and 8, the jaws 22 can be provided with rods 23 having crank arms 24 similar to those hereinbefore described. Bell cranks 50 25 are mounted on the gripping head and have their upper arms connected by rods 26 to the cranks 24. Furthermore the upper arms of the two opposed bell cranks 25 are connected by a spring 27. The parts 55 thus far described are similar to those shown in Figs. 1 to 6 inclusive. The lower arms of the bell cranks in this modified structure, however, are connected by links 28 to a cross head 29 pivotally mounted on a stud 60 30. This stud projects from a slide 31 having a longitudinal slot 32 into which projects a guide screw 33 or the like. A housing 34 is provided for the mechanism described, the lower portion of the slide 31, 65 however, projecting below the housing.

It will be noted that in this modified construction there is a positive connection between the two jaws and should one jaw 22 swing inwardly into engagement with a surface of a wheel, such action being due to the 70 pull exerted by the spring 27, motion would be transmitted through the bell cranks 25 and links 28 to the cross head 29 which would tilt to compensate for any unequal inward movement of the two jaws. 75

When the gripping head is lowered the slide 31 will come into contact with the upper end of the pedestal in the same manner as heretofore described so as to cause the jaws 22 to swing apart and thus allow the car mover to be shifted into position and slide the wheel to be moved. As soon as the gripping head is moved upwardly by means of its lever the jaws 22 will be brought into engagement with opposed faces of the wheel 85 automatically by the action of the spring 27 but will, obviously, adjust themselves so as to equalize the gripping action upon the two faces. 90

What is claimed is:

1. In a car mover the combination with a gripping head and means for moving the same upwardly and downwardly, of opposed gripping jaws carried by the gripping head, a spring, means operated by the spring 95 for holding the jaws normally shifted toward each other, a slide, means controlled by the lowering of the gripping head for shifting the slide relative to said gripping head, and means operated by the slide for moving the 100 jaws against the action of the spring. 90

2. In a car mover the combination with a pedestal, a gripping head and means for moving the gripping head toward and from the pedestal, of opposed gripping jaws carried by the head, yielding means for holding the jaws normally extended toward each other, a member movably connected to the gripping head and movable against the pedestal during the lowering of said gripping head, and means operated by said member when brought against the pedestal for simultaneously shifting the jaws apart. 110 105

3. In a car mover the combination with a gripping head, a pedestal, and means for moving the gripping head toward and from the pedestal, of gripping jaws carried by the head, yielding means for holding said jaws normally drawn toward each other, a slide upon the gripping head and movable against the pedestal during the lowering of said head, and means operated by the slide 115 for shifting the jaws apart. 120

4. In a car mover the combination with a gripping head, a pedestal, and means for moving the gripping head toward and away from the pedestal, of opposed jaws upon the gripping head, yielding means for holding the jaws normally extended toward each other, a slide movable with the gripping 125 130

head and against the pedestal, and separate means operated by said slide for shifting the respective jaws to increase the distance between their gripping faces.

- 5 5. A car mover including a gripping head, a pedestal, means for moving the gripping head toward and from the pedestal, opposed bell cranks connected to the gripping heads, opposed jaws carried by the gripping heads, 10 means for transmitting motion from the respective bell cranks to the adjacent jaws, a slide movably connected to the gripping head and movable against the pedestal during the lowering of the gripping head to

shift relative to said gripping head, and 15 means operated by the slide for shifting the bell cranks to move the jaws apart, and yielding means connecting the bell cranks for holding the jaws normally extended toward each other.

20 In testimony that I claim the foregoing as my own, I have hereto affixed my signature in the presence of two witnesses.
